UNITED STATES PATENT OFFICE.

GEORGE W. BLAKE, OF NEW YORK, N. Y., ASSIGNOR TO JOHN T. KELLY
AND GEORGE M. JONES, OF PITTSBURG, PA.

STOP-VALVE.

SPECIFICATION forming part of Letters Patent No. 224,381, dated February 10, 1880.

Application filed July 11, 1879.

To all whom it may concern:

Be it known that I, GEORGE W. BLAKE, of the city, county, and State of New York, have invented certain new and useful Improvements 5 in Stop-Valves, of which the following is a description, reference being had to the accompanying drawings, forming part of this specification.

This invention, although more particularly 10 designed to be applied to steam-radiators, is applicable to stop-valves for controlling the flow of both steam and water.

The invention consists in the combination, 15 with the stuffing-box of a stop valve or cock, of a chamber permanently attached to the shell of the valve and surrounding said stuffing-box, a cap removable to permit the packing or adjustment of the stuffing-box, and a waste-pipe connected to said chamber below 20 or back of the cap, where it provides for the removal of the cap without disturbing its own connection with the chamber.

Figure 1 represents a longitudinal section 25 of a stop-valve suitable for a steam-radiator or hot-water apparatus, constructed in accordance with my invention, and Fig. 2 an exterior longitudinal view of the same.

The valve here represented does not differ 30 in its general construction from the ordinary globe stop-valve used in connection with steam-radiators and hot-water apparatus for heating purposes, and may occupy either an upright, horizontal, or other position, A being the shell of the valve, provided with suitable 35 inlet and outlet nozzles; B, the valve proper, and C its screw-stem, working through a screw box or nut, D, and stuffing-box E. Here, however, the similarity ends; and permanently attached to and forming part of the 40 shell is a chamber, G, arranged to surround the stuffing-box E, and having attached to it, at or near its lowest part, a waste-pipe, H, for carrying off water which leaks through or past

the stuffing-box, also being provided with a screw or other removable cap, I, on the chamber G, above or beyond the stuffing-box, to prevent water from being blown out of the chamber, excepting through the waste-pipe, and to give access to the valve when required; 45 also to protect the stuffing-box from being improperly removed or unscrewed.

The chamber G, permanently attached to the shell of the valve, essentially differs from a removable chamber provided with a closed top, secured upon the shell below the stuffing-box 55 and provided with a waste-pipe extending from it, as in such construction it is necessary, in order to pack the stuffing-box, to disconnect the waste-pipe from the chamber before removing it. When a joint is thus often broken it 60 is difficult to make it tight, and leakage may take place at the connection between the waste-pipe and the chamber.

As the chamber G is permanently attached 65 to the shell of the valve, the stuffing-box may be repacked as often as necessary by simply removing the cap, and the connection between the waste-pipe and chamber need never be disconnected as long as the valve remains in its place.

What I claim as my invention, and desire 70 to secure by Letters Patent, is—

The combination, with the stuffing-box of a stop valve or cock, of a chamber, G, permanently attached to the shell of the valve and 75 surrounding said stuffing-box, a cap, I, removable to permit the packing or adjustment of the stuffing-box, and a waste-pipe, H, connected to said chamber below or back of 80 the cap, where it provides for the removal of the cap without disturbing its own connection with the chamber, substantially as specified.

GEO. W. BLAKE.
